UNITED STATES PATENT OFFICE.

JESSE S. P. KINMAN, OF DILLON, ILLINOIS.

FOLDING GATE.

SPECIFICATION forming part of Letters Patent No. 639,401, dated December 19, 1899.

Application filed December 15, 1898. Serial No. 699,338. (No model.)

To all whom it may concern:

Be it known that I, JESSE S. P. KINMAN, a citizen of the United States, residing at Dillon, in the county of Tazewell and State of Illinois, have invented a new and useful Folding Gate, of which the following is a specification.

The invention relates to improvements in folding gates.

10 The object of the present invention is to improve the construction of folding gates and to provide a simple, inexpensive, and efficient one, possessing great strength and durability, and adapted to be conveniently operated and 15 quickly opened and closed.

Another object of the invention is to provide a gate which will not be liable to get out of order and which will be unaffected in its opening and closing movement by heavy 20 winds.

The invention consists in the construction and novel combination and arrangement of parts, as hereinafter fully described, illustrated in the accompanying drawings, and 25 pointed out in the claims hereto appended.

In the drawings, Figure 1 is a perspective view of a gate constructed in accordance with this invention. Fig. 2 is a longitudinal sectional view showing the gate folded. Fig. 3 30 is a transverse sectional view on line 3 3 of Fig. 2. Fig. 4 is an enlarged detail perspective view of one end of the supporting-frame. Figs. 5 and 6 are detail perspective views of 35 the front and rear rollers. Fig. 7 is an enlarged detail perspective view of the latch. Fig. 8 is a similar view showing the latch applied to the gate.

Like numerals of reference designate corresponding parts in all the figures of the drawings.

40 1 designates a pair of sills forming a supporting-frame and connected by transverse bars 2 and spaced apart to provide an intervening space, in which a gate 3 is adapted to fold to open it. The transverse bars 2 are embedded in the ground, and the longitudinal sills 1, which are provided at their ends with recesses 4, have beveled or outwardly-inclined upper faces 5, which are reinforced at their 45 highest points at opposite sides of the intervening space or opening 6 with longitudinal strips 7 of suitable metal. The metal strips,

which are secured to the sills by any suitable fastening devices, are adapted to prevent the inner edges of the same from being worn by 55 vehicles passing over them, and the inclined faces of the sills are adapted to prevent obstructions from accumulating and interfering with the operation of the gate.

The recesses 4, which are arranged in pairs 60 at the inner faces of the sills, receive bearing-boxes 8, provided with opposite bearings 9 for journals 10 and 11 of rollers 12 and 13, located, respectively, at the back and front of the gate and secured to the end bars 14 and 15 thereof. The bearing-boxes 8, which are provided at the upper edges of their sides with flanges 16, have their bottoms depressed at 17, and the bearings 9 are located at opposite sides of the depressions 17. The journals of 70 the rollers are arranged in the same plane as the lower faces of the sills, and the depressions 17 receive the depending portions of the rollers. The roller 12, which is located at the back of the gate, is provided with an upwardly-extending arm 18, provided with a groove to receive the lower end of the bar 15, and the other roller 13, which is disposed at the front of the gate, is provided with an arm 19, which is grooved to receive the end bar 14 80 and which is extended laterally of the gate to one end of the roller to provide a stop which abuts against the adjacent sill to limit the movement of the gate.

The gate is composed of the end bars 14 85 and 15, upper and lower horizontal rails 20, and vertical pickets 21, pivoted to the rails and located alternately at opposite sides thereof, as clearly illustrated in Fig. 1 of the accompanying drawings, whereby the gate is adapted 90 to fold compactly when swung downward.

The gate is provided with a pivoted latch-bar 22, adapted to swing upward and downward and provided with a pin or arm 23, adapted to engage a keeper 24 of a latch-post 95 25, which is L-shaped in cross-section and secured at its lower end to the adjacent sill at the inner end of one of the recesses thereof. The front end bar 14 of the gate is provided with a slot 26 to receive the pin or arm of the 100 latch-bar 22, and the inner end of the latter is mounted on a pivot 27. The outer end of the latch-bar is connected by a chain 28 with a pair of links 29, that have their upper ends

attached to operating-levers 30. The operating-levers 30, which are fulcrumed between their ends on posts 31, are adapted to swing horizontally, and their inner ends normally 5 extend toward the center of the roadway and are in position to be readily grasped by the operator. The chain pulls over a cross-bar 32, secured to the post 31 and spaced from the gate a sufficient distance to start the same and 10 to cause it to complete the opening movement by gravity. When the gate is swung upward, its momentum will cause it to complete the closing movement and will carry the arm of the latch in engagement with the keeper of 15 the latch-post.

The invention has the following advantages: The gate, which is simple and inexpensive in construction, is strong and durable, and it is easily operated and is not liable to 20 get out of order. The gate is capable of opening and closing quickly, and its operation is not affected by heavy winds.

Changes in the form, proportion, and minor 25 details of construction may be resorted to without departing from the spirit or sacrificing any of the advantages of this invention.

What I claim is—

1. The combination with a suitable support 30 having an opening, of transverse rollers journaled on the support and provided with arms, one of the arms being extended laterally and arranged to engage the support, and a folding gate carried by the arms and arranged to fold within the said opening, the upward 35 movement of the gate being limited by the said lateral extension of the arms, substantially as and for the purpose described.

2. The combination of a supporting-frame 40 composed of parallel sills spaced apart and provided at their ends with recesses, a post constructed of angle-iron and secured to one

of the sills at one of the recesses thereof, a folding gate having transverse rollers journaled in the said recesses, and a pivoted latch mounted on the gate and adapted to engage 45 the post, substantially as described.

3. The combination of a folding gate provided at one end with a slot, a latch-bar pivoted to the gate, engaging the slot and provided with an arm, a stationary post provided 50 with a keeper arranged to be engaged by the arm of the latch-bar, and operating mechanism connected with the latter, substantially as described.

4. The combination of a folding gate, posts 55 located at opposite sides of the gate, a cross-bar connecting the posts and located beyond the adjacent end of the gate, a chain connected with the gate and extending to the opposite side of the cross-bar and adapted to 60 bear against the latter to throw the gate downward, and operating-levers fulcrumed on the posts and connected with the chain, substantially as described.

5. The combination with a folding gate provided with a latch adapted to retain it in its closed position, of uprights, a horizontal bar or rod supported by the uprights, a pair of horizontally - swinging levers fulcrumed on the uprights, and a flexible connection between the inner ends of the levers and the latch, said flexible connection being extended beneath the horizontal bar or rod and adapted to engage the same, substantially as described. 75

In testimony that I claim the foregoing as my own I have hereto affixed my signature in the presence of two witnesses.

JESSE S. P. KINMAN.
